BACK-DIGGER BOOM CONSTRUCTION

Roy H. Zeilman, Lorain, Ohio, assignor to Thew
Shovel Company, Lorain, Ohio, a corporation
of Ohio

Application July 11, 1936, Serial No. 90,238

4 Claims. (Cl. 214—138)

This invention relates to boom constructions, and more particularly to an improved boom construction adapted to power operated excavating machines of the back-digger type.

5 The back-digger type of excavating machines usually comprises a dipper stick supported at the boom outer end and movement of the boom and dipper stick is controlled by cables secured to the dipper and the upper end of the dipper stick. 10 Due to the dipper stick being supported at the outer end of the boom and extended therebeyond during digging operations, the boom is subjected to considerable stress particularly in compression and torsion. Also, since the cables leading to the dipper are reeved through sheaves disposed generally centrally of the boom, the boom is subjected to a considerable bending moment. The greatest stress will occur in portions of the boom remote from the boom foot or the outer portion of the 15 boom.

20 Heretofore, it has been customary to provide a relatively heavy boom to care for these stresses and due to the difference in operating conditions and boom loading, booms adapted to other type excavating machines have not been adaptable to back-digger machines.

I have provided a boom construction for back-digger machines which is relatively light and a 25 detachable member transmits a large portion 30 of the stresses encountered in the outer portion of the boom. Due to the detachable arrangement of this member power shovel and the like booms may be easily converted to back-digger booms.

35 It is an object of my invention therefore to provide a boom structure for excavating machines having a supplemental stress member in the outer portion of the boom.

40 Another object of my invention is to provide a boom of the above type which is of improved construction relative to the transmission of bending and torsional strains.

45 Another object of my invention is to provide a boom of the above type which may be relatively economically manufactured and assembled and which is of rugged construction compared to the boom weight.

50 Other objects of my invention and the invention itself will become increasingly apparent from a consideration of the following description and drawings wherein:

55 Fig. 1 is an elevational view of a back-digger type of excavating machine embodying my invention;

Figs. 2 and 3 are enlarged plan and elevational views respectively of the boom of Fig. 1;

60 Fig. 4 is a view of the boom of Figs. 2 and 3 prior to insertion of the sheave shafts and supplemental stress member;

Fig. 5 is a sectional view taken along line 5—5 of Fig. 2; and,

Fig. 6 is a fragmentary sectional view taken along line 6—6 of Fig. 3.

Referring now to the drawings, I have illustrated in Fig. 1 an excavating machine of the back-digger type comprising a truck generally indicated at 10 upon which is rotatably mounted a superstructure generally indicated at 11 comprising the power unit and associated mechanism 10 for controlling operation of the boom and supported parts and also movement of the truck. The superstructure 11 is mounted on a turntable indicated at 12 and the boom 13 is hinged at its foot in the usual manner to a forward portion of 15 the turntable. Cables 15 are reeved through sheaves 16 rotatably secured to a dipper stick 17 which pivotally engages boom 13 and jointly with a drag cable 18 secured to a drag bucket 19 at the lower end of the dipper stick controls movement of the boom. The cable 15 is also reeved through sheaves 20 supported on an A frame 21 comprising part of the superstructure mounted on the turntable. A dead end of the cable 15 is secured as indicated at 22 and the opposite end 25 after passing over one of sheaves 20 is wound upon a rotatable hoist drum (not shown) operable in the usual manner.

The drag cable 18 has a dead end secured in the usual manner to the boom adjacent its foot 30 and then passes over one of two transversely spaced sheaves 23 and is reeved through a sheave 24 secured to the drag bucket 19, then it is 35 reversely passed over the second of the pair of sheaves 23 and through a fairlead arrangement 35 to a rotatable drum. In this manner, the boom 40 may be raised or lowered together with the parts supported thereby including the dipper stick and drag bucket through manipulation of the cables 15 and 18 in a manner well understood. The operation of the parts thus far described is well 45 understood and a further description is not believed necessary. The boom 13 comprises side plates 25—25 generally channel-shaped in transverse section tapering from a zone of maximum depth generally centrally of the boom towards each end, the channel form preferably being effected by providing longitudinally extending angles which may be riveted or otherwise integrally secured to the sideplate along the top and bottom edges and with the horizontally extending flanges of the angles inwardly disposed. Transverse spacing plates reinforced by angles may be provided at the lower end of the boom as indicated at 26 and adjacent the outer end of the 50 boom as indicated at 27 which together with a topplate 28 and diagonal tie members 29 comprise transverse spacing members. Rearwardly extending arms at the boom foot indicated at 30 55 are perforated for the reception of hinge pins 60

51 whereby the boom may be hinged at its foot in accordance with common practice. Substantially centrally of the boom the sideplates are perforated in transverse alignment and bearing members 31 integrally secured to the inner face of the sideplates are co-axially perforated for the reception of a shaft 32.

The outer end of the boom comprises a generally U-shaped member 33 suitably secured to 10 side-plates 25 with the projecting U legs being provided with transversely aligned perforations for the reception of a shaft 34.

As best illustrated in Figs. 2 and 5, an element generally indicated at 35 comprising a central 15 generally box-shaped portion 36 and cylindrical end portions 37-37 is provided with a relatively large transverse bore through the central portion 36 for the reception of a tubular member 38, the tubular member 38 preferably prior to assembly 20 with element 35 being bored to co-axially align with the cylindrical end portions 37-37. The cylindrical end portions form bearings for the sheaves 23 which are telescoped thereover and upon projecting the tubular element 38 axially 25 from the outer end of the boom to the position illustrated in Fig. 2 and weldingly securing the same to the member 35 along circular zones indicated at 39 and 40 the shaft 32 may be projected through element 35 and bearing elements 30 31. Suitable spacing washers 41 may be provided intermediate the bearing elements and the outer faces of the sheave hub portion.

The opposite end of tubular element 38 is integrally secured to an axially extending tubular portion 42 of a transversely extending plate element 43 by telescoping portion 42 thereinto and weldingly uniting plate element 43 with the tubular element 38. The plate element 43 is perforated as indicated at 44 whereby it may be secured to a stiffener plate 45 by bolts 46 and nuts 47. The plate 27 is provided with a perforation 48 affording ample clearance for tubular element 38.

The shaft 34 forms a mounting for guide 45 sheaves for cable 15 and also for perforated and rearwardly extending arms 49 of a yoke element 50, the shaft being projected through the perforated arms of member 33 and secured against transverse movement in any suitable manner as 50 by the provision of collars 51. The yoke element 50 is integrally secured to the dipper stick 17 whereby the dipper stick may cooperate with the boom 13 in a manner well understood to control movement of the dipper 19.

55 It will be observed that the elements 35 and 43 are each integrally united with the tubular element 38 whereby torsional stresses encountered when the side of the dipper 19 strikes an obstruction or when rapidly swinging the boom in 60 a lateral direction are absorbed closely adjacent the shaft 34 which transmits such torsional stress to the plate element 43 by the U-member 33 and which stress, in turn, is transmitted to the shaft 32 by tubular element 38 and thence to the boom 65 side plates at substantially the mid-portion of the boom. The stress is then transmitted through the boom proper to the boom foot. Thus, the boom is largely relieved of torsional stresses in its weakest portion or the portion outwardly from 70 the mid-point of the boom. In a similar manner, a large portion of the compression stresses are

transmitted by the tubular element 38 and the boom side plates 25 are proportionately relieved of compression stresses and primarily absorb the bending stresses.

I have described the assembly of the supplemental stress member with the boom as adapting a boom structure illustrated in Fig. 4 to a back-digger boom at the scene of operations or in the field but it is understood that the manner of assembly may be varied as desired or in accordance with best shop practice when assembled 10 at the factory.

Although I have shown and described modifications of my invention I contemplate that numerous and extensive departures may be made therefrom without departing from the spirit of my invention and the scope of the appended claims.

Having thus described my invention what I claim is:

1. A boom construction adapted to back-digger 20 type excavating machines, comprising spaced longitudinally extending side plates, transversely aligned bearing elements in the side plates generally centrally of the boom, a sheave supporting shaft rotatably mounted in the bearing elements, a transversely extending element rigidly fixed to the side plates adjacent their outer ends, and a tubular element rigidly secured to the transverse element at one end of said tubular element and at its opposite end encircling the 30 shaft.

2. A boom construction comprising longitudinally extending side plates, transversely extending spacing members inter-connecting the side plates, transversely aligned bearings in an intermediate portion of the boom, a shaft detachably supported by the bearings, a transverse element integrally secured to the boom adjacent its outer end, and a tubular element extending generally axially of the boom detachably secured at its opposite ends to the shaft and transverse element.

3. A boom construction adapted to back-digger type excavating machines, comprising transversely spaced longitudinally extending side plates, transversely aligned bearing elements in 45 the side plates generally centrally of the boom, a removable shaft rotatably mounted in the bearings, a transverse element integrally secured to the side plates adjacent to the outer end, and a tubular element detachably secured to the transverse element and encircling the shaft adapted 50 to transmit torsional stress from the boom outer end to the boom central portion.

4. The method of converting a boom comprising transversely spaced longitudinally extending 55 side plates into a back-digger boom adapted to withstand severe torsional and compression stresses intermediate the boom outer end and central portions, the method including projecting a tubular element into the boom axially thereof, 60 transversely mounting a shaft having an encircling element associated therewith in the side plates generally centrally of the boom, weldingly securing the inner end of the tubular element to the encircling element, integrally securing a 65 transverse element to the side plates adjacent the boom outer end, and detachably securing the outer end of the tubular element to the transverse element.
